UNITED STATES PATENT OFFICE.

WILMER A. BALDWIN, OF EAST ORANGE, NEW JERSEY.

BUCKLE.

No. 837,657.

Specification of Letters Patent.

Patented Dec. 4, 1906.

Application filed June 10, 1905. Serial No. 264,623.

To all whom it may concern:

Be it known that I, WILMER A. BALDWIN, a citizen of the United States, and a resident of East Orange, county of Essex, State of New Jersey, have invented a certain new and useful Improvement in Buckles, of which the following is a specification.

The object I have in view is the production of a buckle for use upon garments, and more particularly upon the back strap of trousers and waistcoats and the side strap of trousers, the buckle being cheap to construct, of pleasing appearance, easily adjusted, and which will have all of the reliability of a tooth or prong buckle, but which will not injure the fabric such as a prong or tooth buckle will.

I attain these objects by the structure illustrated in the accompanying drawings, in which—

20 Figure 1 is a perspective view of a buckle embodying my invention detached from its supports and the arm swung back and out of engagement with the base. Fig. 2 is a perspective view of the same buckle, but looking in a different direction and showing the arm engaged with the base. Fig. 3 is a sectional view showing the buckle in place and secured to the supporting fabric.

25 In all of the views like parts are designated by the same reference characters.

In carrying out my invention I provide a base 1, preferably of sheet metal, rectangular in form and having a slot 2 for attachment to the loop 3 of the fabric, which is 30 sewed to the garment. The base 1 is provided with ears 4, which are preferably integral and each of which is provided with an opening 5. The edge of the base opposite to the slot 2 is provided with a turned-over portion constituting a ledge 6. This ledge is 35 bent at somewhat less than a right angle, (see Fig. 3,) so as to form a sort of pocket 7.

In connection with the base is employed an arm 8, having lugs 9, which pass through 40 the holes 5 and constitute a means for pivoting the arm. That portion of the arm carrying the lugs is bent at approximately a right angle to the other portion, the bent portion being curved at 10. The edge of the arm 11 45 adjacent to the lugs 9 is straight and without serrations. The other portion of the arm may be provided with an opening 12, which may with advantage be of considerable size. The metal surrounding the opening is curved in 50 cross-section, as shown, so that the outside

surface of the flap will have no sharp corners to injure the fingers of the person applying it.

The strap 13, which is to be adjusted, is passed around the ledge 6 and under the edge 11 of the arm. The free end of the strap 60 may pass under the handle portion of the arm, as shown in Fig. 3, or, if desired, for greater security may pass through the opening 12.

The distance of the edge 11 in advance of 65 the lugs 9 is so adjusted that the edge will bear against the strap 13 as the arm is pivoted and moves into place. The strap will thereby be compressed at this point and seeking to expand will pivot the arm, causing its handle end to engage with the strap. The edge 11 will lie adjacent to the pocket 7 and force a bight of the strap 13 into such pocket. The strap 13 will therefore be pulled against the edge of the ledge 6 and also 70 the edge 11 of the arm, pivoting the latter and pinching the strap between the ledge and the flap. Whatever portion of the strap 13 is in advance of the edge 11 and behind the ledge 6 will be forced into the pocket 7. 80 The tendency of the buckle is to hold the strap with greater security by an increased pull upon it.

The buckle is particularly applicable to satin or silk straps, which it will hold with 85 great security and without injuring them, having no prongs or teeth, as is common in buckles which are liable to tear the delicate silk or satin fabric.

The straps may be adjusted within the 90 buckle with great facility and ordinarily without the need of threading the free end of the strap through the opening 12.

Having now described my invention, what I claim as new, and desire to secure by Letters Patent, is—

A buckle having the following characteristics: a base of metal, rectangular in form and having a slot for attachment to the loop of the fabric which is sewed to the garment, 100 the said base being provided with integral ears, each having an opening therein, the edge of the base opposite to the slot being provided with a turned-over portion constituting a ledge, which ledge is bent at 105 somewhat less than a right angle so as to form a pocket, an arm having lugs which pass through the openings in the ears, that portion of the arm carrying the lugs being bent at approximately a right angle to the 110

other portion, the bent portion being curved, the edge of the arm adjacent to the lugs being straight and without serrations and the other portion of the arm being provided with an opening, the metal surrounding the opening being curved in cross-section, substantially as described.

This specification signed and witnessed this 24th day of May, 1905.
